UNITED STATES PATENT OFFICE.

SAMUEL THOMAS WOLF, OF SALT LAKE CITY, UTAH.

PERMUTATION DOOR-LOCK.

1,067,957.

Specification of Letters Patent.

Patented July 22, 1913.

Application filed June 17, 1911. Serial No. 633,876.

To all whom it may concern:

Be it known that I, SAMUEL THOMAS WOLF, citizen of the United States, residing at Salt Lake City, in the county of Salt Lake and State of Utah, have invented certain new and useful Improvements in Permutation Door-Locks, of which the following is a specification.

This invention relates to permutation door locks.

One object is to provide a combination lock embodying such characteristics that the door cannot be opened from the outside unless the manipulator knows the combination, and to provide further means whereby even if the combination is known the manipulator cannot effect unlocking of the door if it be desired to guard against opening of the door from the outside.

Another object resides in the provision of a comparatively simple, inexpensive, durable and efficient lock of the nature stated, embodying among other characteristics such an arrangement of parts that the lock may be readily assembled and if desired quickly reversed for use either as a right or left-hand door lock.

A still further object resides in the provision of a lock having means whereby the condition of the lock for operating purposes may be ascertained whether in such condition for manipulation by means of elements having pricking engagement or other contact with the manipulator's hand.

With the above and other objects in view, the present invention consists in the construction and arrangement of parts herein-after more fully described, illustrated in the accompanying drawings and particularly pointed out in the appended claims, it being understood that changes may be made in the form, proportion, size and minor details without departing from the spirit or sacrificing any of the advantages of the invention.

In the drawings:—Figure 1 is a horizontal sectional view of the invention. Fig. 2 is a vertical cross sectional view of the invention. Fig. 3 is a vertical longitudinal sectional view through the inner casing. Fig. 4 is a vertical cross sectional view through the outer casing. Fig. 5 is a detail face view of one of the rotatable combination members of the outer casing. Fig. 6 is a

face view of the inner casing. Fig. 7 is a front face view of the outer casing.

Referring now more particularly to the accompanying drawings the reference character 10 indicates the door while the character 11 indicates a casing disposed on the outside of the door, there being a sectional casing on the inside of the door consisting of the main part 12 and the hinged section 13 hinged at 14 and provided with a knob 15 journaled through the section 13 and at its inner end provided with a latch 16 adapted to be turned into engagement with the underface of the top wall of the main part 12 of the inner casing, the purpose of forming the inner casing in sections being so that access may be had thereto and particularly to reverse the position of the locking lever 17 pivoted at 18 in the inner casing for a purpose presently explained.

Journalized through the door and casings is a spindle 19 on the outer end of which slides a device consisting of a sleeve 21 having a knob 20 and at its inner end carrying a plate 22 provided with a finger 23. The plate 22 is bodily movable with the sleeve 21 on the spindle with the finger 23 of the plate working through an opening formed in the ratchet wheel or other rotatable member 25 fixedly secured on the spindle 19 in spaced relation to plate 22, so that the finger 23 may have co-operative engagement with the lugs 26 and 27 of the plates 28 and 29 clamped on the telescoping sleeves 30 and 31 for a purpose presently explained. The plates 28 and 29 are secured on the ratchet wheels or other rotatable members 32 and 33, respectively, and when the plates 28 and 29 are revolved with their respective sleeves 30 and 31 by reason of the finger 23 being brought into engagement with the lugs 26 and 27 of the plates 28 and 29 backward movement of said wheels and plates is prevented by virtue of the spring pawls 34 and 35 engaging said ratchet wheels 32 and 33, there being a spring pawl 36 secured to the outer casing and adapted to engage the large ratchet wheel 25 to effect operation of the indicator pin 48.

The character 37 indicates a spring supporting member secured within the outer casing and having its free end arranged in the path of movement of the finger 23.

Mounted on the spring member 37 is an indicator pin 38 which operates through the opening 39 in the top of the outer casing 11. The purpose of this indicator pin 38 is to indicate to the manipulator of the lock when he has brought both wheels 32 and 33 into position for such operation as will enable the door to be unlocked. For instance, if the manipulator will force the sleeve 21 inwardly as far as it will go the finger 23 of the plate 22 will take up both wheels 32 and 33 because the finger will bridge both lugs 26 and 27 of the plates 28 and 29 on the ratchet wheels 32 and 33, respectively, and then by revolving the plate 22, the wheels 32 and 33 will be turned, and on each revolution of the plate 22 the finger 23 will engage the yieldable support 37 and cause consequent reciprocating movement of the indicator pin 38. By engagement of the pointed end 38 of the indicator pin with the manipulator's finger, which latter he holds over the opening 39, he will know that by two engagements of the indicator pin 38 with his finger that all of the wheels are in condition for such operation as will effect an unlocking of the door.

On the inner end of the sleeve 30 is a disk 40 while on the inner end of the sleeve 31 is a disk 41, there being a disk 42 fixed on the spindle 19, said disks 40, 41 and 42 being confined within the inner casing 12-13.

The character 44 indicates the bolt of the lock which is adapted to operate through openings 45 and 46 at opposite ends of the inner casing 12 and as shown in Fig. 3 the bolt is projecting through the opening 46 and held against inward movement by the tail-piece 47 of the locking lever 17. As will be explained hereinafter the bolt 44 may have movement through the opening 45, depending upon whether the lock is to be used as a right or a left-hand latch.

If the combination of the lock be 678 and if the manipulator desires to open the door, he forces the sleeve 21 inwardly on the shaft 19 as far as possible. This movement of the sleeve 21 positions the finger 23 carried by the plate 22 so that it may engage the lugs 26 and 27 of the plates 28 and 29 on the wheels 32 and 33, respectively. The manipulator then places one of his fingers or one of his hands over the hole 39 in the casing 11 and with his other hand grasps the knob 20 and turns the shaft 19 to the right until he gets two impressions from the indicator pin 38, this indicator 38 being reciprocated by reason of the yieldable element 37 being engaged twice by the pin 23 on the plate 22 of the sleeve 21. The manipulator then knows that the wheels 32 and 33 are in proper position for operation to unlock the lock. The manipulator then places his hand or finger over the hole 49 in the casing 11 and with his other hand turns the knob 20

to the right until he gets six impressions from the indicator 48 which is reciprocated by virtue of its connection with the yieldable element 36 which operates over the teeth of the wheel 25. The manipulator in getting these six impressions from the indicator pin 48 rotates all of the wheels 25, 32, 33, 40, 41 and 42 together because the pin 23 carried by the plate 22 is engaged with the wheel 25 through the aperture therein and is in engagement with the lugs 26 and 27 of the wheels 32 and 33 and because the wheels 41 and 40 being respectively on the same sleeves as are the wheels 32 and 33 with the wheel 42 on the shaft 19 on which the wheel 25 is secured. Thus all the wheels are rotated together when the pin 23 is in engagement with the lug 27 of the plate 29 on the wheel 33 and the knob 20 has been turned to the right until the manipulator has obtained six impressions from the indicator 48. When the wheel 33 has been positioned to effect one point in the combination the wheel 41 is also properly positioned so that its notch 50 may take the part 51 of the lever 17 when the last point in the combination has been effected. After effecting this first point in the combination, the manipulator then pulls outwardly on the knob 20 to pull the sleeve 21 and the finger 23 on the plate 22 away from the lug 27 on the wheel 33. The manipulator now grasps the knob 20 and turns it to the right until he gets one more impression through the hole 49 from the indicator pin 48. When this additional impression has been received, the manipulator knows that by reason of the pin 23 on the plate 22 passing through the aperture in the wheel 25 and being in engagement with the lug 26 on the plate 28 carried by the wheel 32 that the latter and the wheel 40 have been properly positioned to effect the second step in the combination with the notch 50 of the wheel 40 in position to take the part 51 of the lever 17 when the last step in the combination has been effected. Now that the second step in the combination has been effected, the manipulator grasps the knob 20 and on an outward pull of the same releases the pin 23 of the plate 22 from engagement with the lug 26 on the plate 28 carried by the wheel 32. By then placing his hand over the hole 49 and turning the knob 20 to the right he rotates the wheel 25 until he gets one impression from the indicator 48. When the wheel 25 has been given this additional turn, the wheels 32, 33, 41 and 40 are not turned but the wheel 42 is turned when the wheel 25 is given the last turn because the wheels 42 and 25 are fixed to the shaft 19. When the manipulator receives this last impression from the indicator 48 through the hole 49 he thereby knows that he has effected such manipulation of the wheels as to per-

mit the lever 17 to be moved on its pivot 18 to throw the part 51 of the lever 17 into the notches 50 of the wheels 40, 41 and 42 and thereby permit the tail piece 47 of the lever 17 to be lifted from behind the latch 44 which latter may now be moved inwardly of the casing by manipulation of the shifting lever 52 pivoted at 53 in the slot 54 of the casing 11 and also extending through the slot 55 in the door 10 to engage the notch 56 in the slideable bolt 44. It will thus be seen that the indicator pin 48 is reciprocated all the time with the proper combinations being effected to unlock the door and that the indicator pin 38 is intended only for the purpose of placing the wheels 32 and 33 in such position as to start operation of the lock to effect the combination so that the door may be opened. In other words, the indicator pin 38 gives two impressions while the indicator pin 48 gives the remaining impressions.

Assuming that the lock described is used as a right-hand door latch and it is desired to use it as a left-hand door latch it is simply necessary to unlock the latch 16 of the inner casing 12-13 and shift the part 13 on its pivot 14 when access may be had to the sectional or inner casing and permit the locking lever 17 to be reversed so that its tail-piece 47 may have co-operative engagement with the right-hand end of the bolt 44. The sectional casing may then be closed and the operation heretofore described for effecting a locking and unlocking repeated and in order that the locking lever 17 may be operated so as to disengage its tail-piece 47 from engagement with the bolt 44 the locking lever pivot 18 is preferably in the form 40 of a rotatable shaft on which the lever 17 is fixed, and this shaft is indicated at 57 and at its outer end provided with a knob 58 so that it may be rotated in its bearings in the outer casing and in the door 10 as shown 45 clearly in Fig. 2.

In the event that it be desired that the lock be not manipulated from the outside to open the door there is preferably provided a pivoted latch 58' on the inner side of the 50 sectional casing 12-13. This latch 58' may be thrown in either direction on its pivot to engage the lug 59 operating in the slot 60 so that whether the lock is for the right or left-hand side of a door, the bolt 44 cannot be 55 opened, as may be seen particularly by reference to Fig. 6.

From the foregoing, it will be understood that the ratchet wheels 32 and 33, like the ratchet 25, are rotatable members and that the ratchet wheels 32 and 33 rotate their respective sleeves so as to correspondingly rotate the disks 40 and 41 at the opposite ends of their sleeves. The ratchet wheels 32 and 33 are what may be termed rotatable members 60 having, by virtue of the plates 28 and 29,

suitable projections 26 and 27 respectively, whereby these ratchet wheels 32 and 33 may be regarded as rotatable members provided with projecting portions designed for engagement by the aforesaid pin 23 upon rotation of the knob 20, sleeve 21 and plate 22.

By having the inner casing composed of sections, it has the advantages other than to permit access to the interior thereof so that the parts may be reversed, in that this sectional casing gives access to the disks 40, 41 and 42 so as to change them to any combination desired. Moreover, by virtue of this sectional casing, if a person should be out late at night, and a person on the inside wished to retire before the absent one came back, and especially if that absent one did not understand the combination, it would simply be necessary to raise the hinged section 13 and push the bolt 44 into its proper locking position and the lever 17 so that its part 51 would enter the notches 50 in the disks 40, 41 and 42, in which event, the absent one upon his return could readily shift the bolt to unlocked position from the outside. Suppose a member of one's family should be out late and those on the inside wished to retire, and assuming that those on the outside knew the combination, those on the inside could simply raise the hinged section 13 to the casing 12 and push the bolt 44 forward, turn the lever 17 down, and then turn the disks 40, 41 and 42 so that the notches 50 cannot be entered by the part 51 of the lever 17. The lock will then be locked just the same as one would lock it from the outside and those on the inside are securely locked in while those on the outside may unlock the door, without disturbing those on the inside.

What is claimed is:—

1. In a lock, in combination, inner and outer casings, a spindle journaled in the casings, sleeves on the spindle which project into both casings, sets of rotatable members 110 mounted on the sleeves and also on the spindle with one set disposed in the inner casing and the other set disposed in the outer casing, the rotatable members of one set each having a notch, a bolt slideable into and out of one of the casings, a lever pivotally mounted in one of the casings and having its tail piece normally behind the bolt to hold the latter normally against inward movement and at its opposite end provided with a lateral projection, a device arranged to effect rotation of the spindle to rotate the rotatable members in the same direction to predetermined positions with the notches of the notched set of rotatable members 115 brought into alignment, means whereby said lever may be shifted on its pivot subsequent to the positioning of said rotatable members so as to shift the tail part of the lever out of the path of movement of said bolt and to 120 125 130

throw its lateral projection into the alining notches of said notched set of rotatable members, and means for shifting the bolt inwardly after said lever has been moved out of the path of the movement of the bolt.

2. In a lock, in combination, a casing, a spindle journaled in the casing, sleeves on the spindle, rotatable members mounted on

the sleeves and each provided with a projection, a rotatable member mounted on the spindle and provided with an aperture, a bolt slideable into and out of the casing, a lever pivotally mounted in the casing and

18 disposed normally behind the bolt to hold the latter normally against inward movement, another sleeve slideable on and rotatable with the spindle and provided at one

20 end with a knob, a plate carried at the inner end of the last mentioned sleeve and provided with a finger adapted to project through the aperture of the rotatable member on the spindle for engagement with the

ber on the spindle for engagement with the projections of the rotatable members on said sleeves whereby the rotatable members may be rotated, an indicator actuated by said finger, an indicator actuated by the rotatable

member on the spindle, means whereby said lever may be lifted out of the path of movement of the bolt, and means for moving the bolt inwardly subsequent to movement of said lever out of the path of movement of the bolt.

3. In a lock, in combination, a casing provided with apertures, indicators mounted in the casing for projection through said apertures, a spindle journaled through the casing, a spindle rotating device on the spindle whereby the latter may be rotated, rotatable members mounted on the spindle within the

40 members mounted on the spindle, a thin
casing for rotation with the spindle, means
interposed between the spindle rotating de-
vice and the aforesaid rotatable members
to rotate the latter together and to actuate
one of said indicators, another rotatable

45 member in the casing operable by said spindle rotating device to actuate the other of said indicators, a bolt slidable into and out of the casing, means for holding the bolt normally against inward movement, means

normally against inward movement, means for moving said bolt holding means out of the path of movement of the bolt, and means whereby the bolt may be moved into the casing.

4. In a lock, in combination, a casing provided with apertures, indicators mounted in the casing for projection through said apertures, a spindle journaled through the casing, a knob on the spindle whereby the latter may be rotated, rotatable members on the spindle within the casing for rotation with the spindle and provided with projections, means arranged within the casing and having operative connection with said knob and including a finger for engagement with the projections of said rotatable members to

rotate the latter and to actuate one of said indicators, another rotatable member mounted in the casing and adapted to operate the other of said indicators, a bolt slideable into and out of the casing, means for holding the bolt normally against inward movement, and means whereby the bolt may be moved into the casing. 70

5. In a lock, in combination, a casing provided with apertures, indicators mounted in the casing for projection through said apertures, a spindle journaled through the casing, a knob on the spindle whereby the latter may be rotated, rotatable members on the spindle within the casing for rotation with the spindle and provided with projections, means arranged within the casing and having operative connection with said knob and including a finger for engagement with the projections of said rotatable members to rotate the latter selectively and to actuate one of said indicators, another rotatable member mounted in the casing and rotatable by the said finger and adapted to operate the other of said indicators, a bolt slidable into and out of the casing, means for holding the bolt normally against inward movement, means whereby the bolt may be moved into the casing, the bolt having a projection, and separate means arranged for engagement with the projection on the bolt to prevent inward movement of the bolt. 75 80 85 90 95

6. In a lock, in combination, a casing provided with apertures, indicators mounted in the casing for projection through said apertures, a spindle journaled through the casing, a spindle rotating device on the spindle whereby the latter may be rotated, rotatable members mounted on the spindle within the casing for rotation with the spindle, means interposed between the spindle rotating device and the aforesaid rotatable members to rotate the latter selectively to actuate one of said indicators, another rotatable member in the casing operable by said spindle rotating device to actuate the other of said indicators, a bolt slidable into and out of the casing, means for holding the bolt normally against inward movement, means whereby the bolt may be moved into the casing, and means arranged to engage the bolt to prevent inward movement thereof. 100 105 110 115

7. In a lock, in combination, inner and outer casings, the outer casing having apertures, indicators mounted in the latter casing for projection through said apertures, a spindle journaled in the casing, telescoping sleeves on the spindle which project into both casings, sets of rotatable members mounted on the sleeves and also on the spindle, the rotatable members of one set each having a notch, a bolt slidable into and out of the inner casing, a shaft journaled through the outer casing and extending into the inner casing, a lever confined in the 130

inner casing and mounted on the inner end of said shaft and having a tail-piece disposed normally behind the bolt to hold the bolt normally against inward movement 5 and at its opposite end provided with a lateral projection, a spindle rotating device arranged to effect rotation of the spindle to rotate the rotatable members in the same direction together and selectively to predetermined positions with the notches of the notched set of rotatable members brought 10 into alinement and to simultaneously operate said indicators, a knob on the outer end of the aforesaid shaft to rotate the latter 15 and lift the tail piece of said lever out of the path of movement of said bolt and to throw the lateral projection of said lever into the alining notches of said notched set of rotatable members, and means for shifting 20 the bolt inwardly after said lever has been moved out of the path of movement of the bolt.

8. In a lock, in combination, inner and outer casings, the outer casing having apertures, indicators mounted in the outer casing for projection through said apertures, a spindle journaled in the casing, telescoping sleeves on the spindle which project into both casings, sets of rotatable members 30 mounted on the sleeves and also on the spindle, the rotatable members of one set each having a notch, a bolt slideable into and out of the inner casing, a shaft journaled through the outer casing and extending into

the inner casing, a lever confined in the inner casing and mounted on the inner end of said shaft and having a tail piece disposed normally behind the bolt to hold the bolt normally against inward movement and at its opposite end provided with a lateral projection, a spindle rotating device arranged to effect rotation of the spindle to rotate the rotatable members to predetermined positions with the notches of the notched set of rotatable members 45 brought into alinement and to simultaneously operate said indicators according to the positioning of said rotatable members, a knob on the outer end of the aforesaid shaft to rotate the latter and lift the tail piece of said lever out of the path of movement of said bolt and to throw the lateral projection of said lever into the alining notches of said notched set of rotatable members, means for shifting the bolt inwardly after said lever has been moved out of the path of movement of the bolt, the bolt having a lateral projection, and means for engagement with the lateral projection of the bolt to prevent inward movement 60 thereof after the said lever has been moved out of the path of movement of the bolt.

In testimony whereof I affix my signature in presence of two witnesses.

SAMUEL THOMAS WOLF.
